UNITED STATES PATENT OFFICE

2,602,015

MERCHANTISE CABINET

Harold H. Newman, Brooklyn, N. Y.

Application September 14, 1949, Serial No. 115,718

1 Claim. (Cl. 312—138)

1

My present invention relates to cabinets for the display and dispensing of merchandise, and aims to provide certain improvements therein. More particularly it relates to such cabinets which are adapted for self-service or attendant service, as desired.

In most theatre and in many hotel lobbies, as well as in many restaurants, cafeterias and food markets, display and dispensing cabinets are stationed at which confectionery or other food products may be closely viewed by purchasers and quickly dispensed by an attendant, when ordered. Many of these cabinets are of the self-service type so that a customer may help himself and pay for the merchandise thus taken, either to an attendant stationed behind or adjacent the cabinet or to a cashier at some remote point, as in a cafeteria. Under certain conditions, for example, in the lobby of a theatre just before show time or when passers-by are numerous, to prevent loss by pilfering it becomes prudent to have such cabinets wholly attendant served and to preclude direct access to the merchandise by the purchasers. Also, in cases where the law requires that the food products be covered, it is desirable to have such cabinets normally closed both at the front and rear and serviced by an attendant at the rear of the cabinet.

It is accordingly an object of my invention to provide a display and dispensing cabinet so designed and constructed as to function either as a self-service or attendant serviced unit. A further object is to provide a cabinet of the type specified, which can be converted in a matter of seconds, with but little effort, from a self-service type to an attendant serviced type. A further object is to provide such cabinet wherein the display of the merchandise is not lessened by reason of the conversion from the self-service to the attendant serviced form. A further object is to provide a cabinet of the character set forth which will be suitable for the sale and dispensing of confectionery and food products which must be refrigerated to maintain their freshness in both appearance and quality. Still another object is to provide such cabinet which will be pleasing in appearance and simple and compact in construction.

The foregoing and other objects of my invention not specifically enumerated I accomplish by providing a cabinet having the display compartment thereof provided with protective transparent front and top sections which are hingedly connected together and adapted, when the transparent top section is moved about its hinge, to lie in a common plane with the front transparent section that the protective sections can be moved downwardly as a unit out of view to render the merchandise displayed accessible from in front of the cabinet. The cabinet is preferably also provided with a multiple sectioned, hingedly connected rear top portion which is adapted to be

2

opened about the hinged connections to lie in parallel relation to the rear wall of the compartment wholly within the contour of the cabinet. The cabinet is also provided with novel means for conducting and circulating refrigerated air to the merchandise on display. The invention will be better understood from the detailed description which follows when considered in connection with the accompanying drawings illustrating a preferred embodiment, and wherein:

Figure 1 shows a front elevation of a cabinet embodying my invention, the protective transparent front and top sections of the cabinet being closed.

Fig. 2 shows a transverse section of the cabinet of Fig. 1 taken substantially along the plane of the line 2—2 of Fig. 1.

Fig. 3 shows a transverse section of the cabinet of Fig. 1 taken substantially along the plane of the line 3—3 of Fig. 1.

Referring to the drawings, in the various figures of which the same reference numerals are employed to designate corresponding parts, the cabinet of my invention may be said to comprise a front wall 10, a rear wall 11, a top wall 12 and side walls 13, the cabinet being divided primarily into a display and dispensing compartment 14 and a refrigerating compartment 15.

The display compartment 14 as herein shown has an inclined bottom wall 16 extending from the front wall to the rear wall, said bottom wall having openings 17 therethrough, for a purpose which will presently appear. Mounted on the inclined bottom wall 16 are a plurality of horizontally disposed shelves 18 which preferably extend the complete width of the cabinet and are each provided with a front guard wall 19, preferably of glass, or other transparent material, so that merchandise supported on the shelves will be visible from both the front and top of the cabinet. Preferably the shelves 18 are formed of foraminous material, for a purpose which will presently appear. The display and dispensing compartment 14 has a displaceable transparent protective front wall 20 and a displaceable transparent protective top wall 21, the said walls 20 and 21 being hingedly connected along their adjacent ends preferably by a piano hinge 22. Where said walls are formed of glass it will be apparent that the edges of the glass may be protected with metal channel members 23, in a manner well known in the art, and the piano hinge mounted on such metal channel members. The side walls 13 adjacent the front of the cabinet are provided with guide rails 24 which extend the full height of the cabinet and serve as guides along which the upright lateral ends of the front wall 20 may ride when it is sought to open the front of the display compartment 14. As shown, the top transparent wall section 21 is normally disposed at substantially a right angle to the front transparent wall 20 and is adapted to be supported in

30
35
40
45
50
55
60

such position by horizontal ledges or rails 25 extending inwardly from the side walls 13 adjacent the top thereof. The hinged connection between the top transparent wall section 21 and the front wall section 20 is such that the top wall section may be pivoted about its hinge 22 to enable said walls to be disposed in a common plane, and when so disposed it will be apparent that the top wall section 21 will form a continuation of the front wall section 20 and can likewise ride up and down along the guide rails 24. To facilitate the movement of the walls 20 and 21 along the guide rails the bottom of the wall 20 has connected thereto flexible tapes 26 constituting parts of spring counterweight or balancing mechanisms 27 of a well known type, said balancing mechanisms being mounted at the inner surfaces of the side walls 13 within the display compartment 14. These counterweight or balancing mechanisms are held in relatively flat casings and do not impair the visibility of the merchandise within the compartment 14. Preferably the front of the cabinet below the display compartment has an opaque rigid wall or panel 28 which serves as a protective shield for the transparent front wall and top wall sections 20 and 21 when they are disposed behind the wall 28, and expose the display compartment 14 for self-service of customers.

The top wall of the compartment rearwardly of the top transparent wall section 21 is preferably sloped downwardly toward the rear of the cabinet and is hinged at its lower edge to the top of an inset rear panel 29 through a piano hinge 30. The rear top panel of the cabinet is preferably formed of longitudinal sections 31, 32 which are hinged together by a piano hinge 33, said hinge being so disposed with relation to the hinge 30 that the rear top panel may be first pivoted about the hinge 30 and then about the hinge 33 to dispose the top panel sections 31 and 32 in face to face relation, parallel to the rear panel 29, as best shown in Fig. 3. To enable the top panels or sections of the cabinet which provide the top wall of the display compartment to be locked so as to preclude access to the display compartment, the forward edge of the panel 31 is formed with an overhanging lip 34 which is adapted to overlie and engage a protruding lip 35 on the protective channel member 23a which is mounted at the rear of the top transparent wall section 21 and a suitable locking means 36 mounted in the panel 31 may serve to lock the panels in closed relation.

Below the display compartment 14 the cabinet may be provided with the refrigeration compartment 15 containing refrigerating apparatus (not shown), and with additional storage space or refrigerated compartment 37, access to which may be gained through slideable doors 38. For circulating refrigerated air from the compartment 37 to the display compartment 14, the bottom wall 16 of the latter is formed with a spaced partition 39 providing a chamber 40 to which refrigerated air may be supplied by a duct 41 leading from a blower 42 mounted in the refrigerated air compartment 37. It will thus be seen that refrigerated air may be drawn from the compartment 37 through the duct 41 into the chamber 40 and from there distributed through the opening 16 to the spaces below the perforated sleeves 18 and through the perforations therein to the compartment 14. To provide for complete circulation of such refrigerated air the end of the compartment 40 opposite that at which the blower 42 is mounted may be provided with an outlet duct 43 75

which leads back to the refrigerated compartment 31. The cabinet as a whole may be formed with a front and rear inset 44 at the floor level to provide the space for purchasers and the attendant.

From the foregoing detailed description it will be apparent that merchandise displayed on the shelves 18 of the cabinet will be readily viewable from in front of and above the cabinet when the displaceable transparent protective walls 20 and 21 are in either the position shown in Fig. 2, where self-service of such merchandise is not possible, or, as shown in Fig. 3, where such self-service is available. Of course, the rear top panels 31, 32 of the display compartment may be either open or closed, depending on the type of service the cabinet is called upon to render. Obviously where the cabinet is attendant operated the rear top panels will be open and the front of the display compartment may be open or closed. In cases such as a cafeteria system the top rear section may be left closed. It will also be apparent that the merchandise displayed, if of a perishable character, will be protected by refrigerated air, the passage of which through the display compartment of the cabinet may be controlled, as desired. Where such cabinets are disposed in a theatre or hotel lobby and unattended, the cabinet as a whole may be closed and locked by positioning the front and top walls of the display compartment as shown in Fig. 2 and locking the rear top wall section through the locking means 36.

While I have shown and described a preferred embodiment of my invention it will be understood that changes in details of construction thereof may be resorted to within the range of mechanical and engineering skill without departing from the spirit of the invention as defined in the appended claim.

What I claim is:

A merchandise cabinet comprising a display compartment having front, top and rear walls, said compartment being viewable from in front of and above the cabinet, the top wall of the compartment being formed of longitudinally divided front and rear sections, said sections being independently displaceable to provide access to the compartment from either the front, top front or top rear of the compartment, the front top wall section of the compartment being hingedly connected to the front wall of the compartment and adapted to be moved about its hinged connection into the plane of the front wall, guide rails in the cabinet along which the lateral upright ends of the front wall are rideable and along which rails the front top wall section is also movable when said wall section is brought into the plane of the front wall of the compartment.
